CLAIM

The ornamental design for a bottle, as shown and described.

DESCRIPTION

FIG. 1 is a perspective view of a bottle showing our new design;

FIG. 2 is a front elevation of FIG. 1, the rear and side elevations are the same except for the conventional screw threading on the bottle neck and the placement of the indentations on the base;

FIG. 3 is a side view of the bottle depicted in FIG. 2 representing a partial rotation of the bottle about its vertical center axis from the front view depicted in FIG. 2;

FIG. 4 is a top view the bottle depicted in FIG. 2;

FIG. 5 is a bottom view of the bottle depicted FIG. 2;

FIG. 6 is a perspective view of a second embodiment of a bottle as depicted in FIG. 1;

FIG. 7 is a front elevation of FIG. 6, the rear and side elevations are the same except for the conventional screw threading on the bottle neck and placement of the indentations on the base;

FIG. 8 is a side view of the bottle depicted in FIG. 7, representing a partial rotation of the bottle about its vertical center axis from the side view depicted in FIG. 7; and, FIG. 9 is a top view of the bottle depicted in FIG. 7.

The bottom of the second embodiment is the same as the bottom of the first embodiment.
